(57) **CLAIM**

The ornamental designs for an industrial robot, as shown and described.

DESCRIPTION

FIG. 1 is a front elevational view of the industrial robot; FIG. 2 is a left-side elevational view thereof; FIG. 3 is a right-side elevational view thereof; FIG. 4 is a rear elevational view thereof; FIG. 5 is a top plan view thereof; FIG. 6 is a bottom plan view thereof; FIG. 7 is a first perspective view thereof; and, FIG. 8 is a second perspective view thereof. The dot-dash chain lines depict boundaries of the claimed subject matter, and thus form no part of the claimed design. The broken lines depict unclaimed parts of the industrial robot, and thus form no part of the claimed design.

1 Claim, 4 Drawing Sheets(56)
